(57) **CLAIM**

The ornamental design for a microtrencher blade, as shown
and described.

DESCRIPTION

FIG. 1 is a left side view of our microtrencher blade, the
right side being a mirror image thereof.

FIG. 2 is a top front left side view thereof.

FIG. 3 is a back top right view thereof.

FIG. 4 is a front top right view thereof.

FIG. 5 is an edge view thereof.

FIG. 6 is an expanded fragmentary edge view of the blade
as shown in the call-out of FIG. 5.

FIG. 7 is an expanded fragmentary left side view of a tooth
as shown in the call-out location of FIG. 1.

FIG. 8 is a close up right side view thereof; and,

FIG. 9 is an expanded fragmentary view of the call-out
location shown in FIG. 2.

The broken line elements are included for the purposes of
illustrating portions of the microtrencher blade and form no
part of the claimed design. The line indicated by alternating
dot-dash is a boundary line, the interior of which does not
form any part of the claimed design. FIGS. 1, 2 and 5
represent callout locations for the expanded fragmentary
views shown therein, with the borders of the call-out locations
shown by lines of alternating lengths. Lines included
with thin weight and which do not extend to any adjacent
line are provided to show contour.
